SERVING TRAY FOR FRANKFURTER ROLL SANDWICHES

Harry Silos, Fairfield, Conn.

Application March 2, 1953, Serial No. 339,617

3 Claims. (Cl. 65—15)

This invention relates to a serving tray for frankfurter roll sandwiches and the like. As is well known, frankfurter rolls are elongated, and as they are baked while lying on one side the dough flattens out during the baking so that the roll is oblong in cross section. In making the sandwich the roll is slit longitudinally from one side edge and the frankfurter placed in the slit roll, and mustard or other relish may or may not be added. As the roll was slit longitudinally from one side, if the filled roll is placed on a dish or other similar support, because of its elongated section it will not remain upright on the opposite closed side edge from the slit, but will roll over on the flattened side, spilling the frankfurter and the relish.

It is an object of this invention to provide a serving tray for the filled frankfurter rolls, which will be of very simple construction and attractive in appearance, and which will hold the filled roll or the completed sandwich in an upright position on the closed side edge opposite the slit in the roll and prevent its tipping over, and thus prevent the contents from spilling out of the sandwich, and also to provide a construction whereby such a filled roll or sandwich may be readily gripped by a hand of the customer and raised from the holder without spilling the contents.

With the foregoing and other objects in view, I have devised the construction illustrated in the accompanying drawing forming a part of this specification. It is, however, to be understood the invention is not limited to the specific details of construction and arrangement shown, but may embody various changes and modifications within the scope of the invention.

In this drawing:

Fig. 1 is a side elevation of a serving tray comprising my invention;

Fig. 2 is a top plan view thereof, and

Fig. 3 is a transverse section substantially on line 3—3 of Fig. 2.

The tray may be made of different forms and constructions, but a very simple and effective form is shown in the drawing. It comprises a body and base member or support 5 of any suitable material, preferably some sheet material, such, for example, as sheet metal, plastics, or a stiffened fibrous material such as cardboard, and this member as shown comprises a substantially flat top wall 6 with downwardly extending end walls or flanges 7 and similar side walls or flanges 8 at the opposite edges of the top wall to strengthen and stiffen it. These flanges may also provide means for securing supporting legs 9 to the body member, although supporting legs are not necessary. However, short legs are preferred to improve the appearance of the device and to support the holders a short distance above the top of a serving counter, for example. These legs may be of any suitable form, but a simple and effective form is that shown in the drawings comprising angular shaped members of sheet material secured to the flanges 7 and 8 at the corners of the body by any suitable means, such, for example, as the rivets 10.

2

Mounted on the top of the body member or support are one or more holders 11 for the filled frankfurter rolls or the completed sandwiches, one of which is shown at 12. Any suitable number of these holders may be used as found desirable or necessary, and of course for a larger number the body member or support 5 would be made of the necessary length to carry them. These holders, as shown, comprise transversely curved trough-shaped members, preferably formed of sufficiently rigid sheet material, resting on the top wall 6 of the support and secured thereto by any suitable means such, for example, as the rivets 13. These members are elongated members including transversely spaced side walls 14 spaced a proper distance to support the filled frankfurter roll or sandwich 12 in an upright position with the closed longitudinal side edge 15 of the roll 16 resting on the bottom of the trough and the opposite sides resting on the edges of the side walls of the holder, as shown in Fig. 1, and with the open side facing upwardly with the frankfurter or relish 17 exposed. This shape of the holder and the side walls effectively holds the filled roll in the upright position and prevents it from turning or tipping over on its side, which would thus spill the frankfurter or other contents of the sandwich from the roll. To facilitate gripping of the sandwich or filled roll, and lifting it from its holder, the opposite side walls 14 of the holder are cut away intermediate their lengths, relatively large transverse recesses as indicated at 18, to expose the opposite sides of the filled roll in the holder. As these sides are exposed they permit ready gripping of the filled roll with the thumb and fingers of the hand of the customer, and ready removal of the sandwich from the holder.

The device is designed primarily to be used on the serving counter of a frankfurter sandwich stand. It is common practice at the present time for the server to place the filled roll in a paper napkin and place it on a plate or similar article on the counter as soon as he finishes the sandwich, permitting the customer to pick up the filled sandwich as the server turns to prepare other sandwiches. Because of the elongated and flattened cross section of the roll, and the fact it is slit longitudinally from one side edge when cut to receive the frankfurter, it will not stand up on this edge, but will turn over on its side, with consequent spilling of the frankfurter and relish. With this device, however, instead of placing the sandwich on a plate, it is merely placed on its closed longitudinal side edge in one of these holders which may be on the counter, with the open side up, as shown in Fig. 1, the paper napkin being omitted in the drawing to simplify it, and this holder effectively supports this filled sandwich in this position and prevents it tipping or turning over, with consequent spilling of the contents of the sandwich. It effectively holds the sandwich in this position until picked up by the customer, relieving the server or counterman from the necessity of holding the sandwich until the customer takes it, and permits him to immediately start completing other sandwiches without loss of time. Because of the intermediate cut-away portions 18 of the side walls 14 there is no difficulty experienced by the customer when lifting the sandwich from the holder.

Having thus set forth the nature of my invention, I claim:

1. A serving tray of the character described comprising a body member forming a support including a substantially flat top wall and downwardly extending flanges at its edges, a holder for a filled frankfurter roll sandwich on the top of and forming a permanent part of the support comprising elongated transversely concavely curved walls forming an elongated upwardly facing recess open at its opposite ends, said walls at the sides of the recess extending above the top wall of the base member and of suffi-

cient height and laterally spaced a distance to form supports for the opposite sides of the frankfurter roll sandwich and hold it with its open longitudinally slit side edge on top and prevent it from tipping over, and the upper edges of the opposite side walls of the holder being longitudinally concavely curved at substantially their mid-length forming relatively large recesses at the top edges of said walls to permit free gripping of the sandwich.

2. A serving tray of the character described comprising a body and base member forming a support and including a substantially flat top wall and downwardly extending flanges at its outer edges, a series of parallel holders for frankfurter roll sandwiches on top of and forming a permanent part of said member each comprising elongated transversely concavely curved walls forming an elongated upwardly facing trough shaped recess, said walls at the sides of the recess extending above the top wall of the base member of sufficient height and laterally spaced a distance to form a support for the side walls of a filled frankfurter roll sandwich and hold it with its open longitudinally slit side edge on top and prevent it from rolling over on its side, the upper edges of the opposite side walls of the holder being longitudinally concavely curved at about their mid length forming relatively large recesses in the top edges of said walls to permit free gripping of the sandwich, and adjacent holders

being spaced laterally from each other a distance sufficient to permit gripping of each individual sandwich entirely independently of the others.

3. A serving tray according to claim 2 in which the body and base is a substantially rectangular member, and there are downwardly and outwardly inclined angularly shaped supporting legs at the corners thereof.
